UNITED STATES PATENT OFFICE.

GUSTAV BERNHARD GERLACH, OF CRIMMITZSCHAU, GERMANY,
ASSIGNOR OF ONE-HALF TO KETTLING & BRAUN, OF CRIM-
MITZSCHAU, SAXONY, GERMANY.

MACHINE FOR STEAMING CLOTH.

No. 810,271.

Specification of Letters Patent.

Patented Jan. 16, 1906.

Application filed April 5, 1905. Serial No. 254,068.

To all whom it may concern:

Be it known that I, GUSTAV BERNHARD GERLACH, a subject of the German Emperor, residing at Crimmitzschau, Kingdom of Saxony, 5 Germany, have invented certain new and useful Improvements in Machines for Steaming Cloth, of which the following is a full, clear, and exact specification.

The present invention relates to machines 10 for steaming cloth, and has for its object to do away with the inconveniences produced by the condensed water. It is well known that if this water is not readily removed the cloth is stained and loses much of its value.

15 In order to do away with the condensed water, the invention consists principally in a scraper which removes from the inner surface of the perforated steaming-cylinder the small particles of condensed water and conveys them through a spout to the outside of the frame of the machine.

20 In the accompanying drawings, forming part of this specification, Figure 1 is a longitudinal section of the cylinder of my cloth-steaming machine. Fig. 2 is a cross-section on line xx of Fig. 1. Fig. 3 shows a cross-section through the cylinder of a modified construction.

The steaming-cylinder a , made of perforated sheet metal or of wire-gauze, is secured in 25 head-rings b , which can freely and easily revolve in ball-races or caps c , secured on the frame of the machine. Rotation can be imparted to the cylinder a by belts or any other convenient known means, or the rims of the 30 head-rings may be cut so as to present gear-wheels, to be moved by suitable pinions. Between the stationary ball-races c and within the mantle of the perforated cylinder a a spout d is secured, the bottom of which is inclined, slightly lowering from the middle toward both side frames of the machine, as 35 shown in Fig. 1. The spout d serves for taking up the steam-pipe e , which is partly covered by a curved sheet-metal plate f . To one 40 edge of the spout d a curved sheet-metal plate g , preferably of a resilient nature, is secured, carrying at the upper edge a scraper h , which is slightly pressed against the inside of mantle of cylinder a .

45 i represents pipes serving to convey the condensed water collecting on the bottom of spout d .

In using this steaming-cylinder the cloth is wound around the same in the ordinary manner and steam is admitted through the steam-pipe e , provided below with small holes. The steam fills the interior of the cylinder, acts on the cloth, and gradually condenses on the inner walls in the form of small water-bubbles, which are wiped off by the scraper h and 55 drop as water on the latter, as well as on plate g , downward into the spout d , which conveys it on its inclined bottom toward both ends. Finally the water flows off through pipes i 60 on both ends.

Without departing from the nature of the invention, the elastically-supported scraper h on the inner surface may be substituted by a plurality of slats k , as indicated in Fig. 3, and extending longitudinally through said 70 cylinder and being secured to its inner surface, so that the water of condensation forming at the lower parts is constantly lifted, while the cylinder revolves and drops into the spout d .

Having thus described my invention, what I claim is—

1. In a machine for steaming cloth a perforated cylinder in combination with a scraper 80 adapted to remove from its inner surface the particles of the condensing water substantially as described.

2. In a machine for steaming cloth a perforated cylinder with end rings revolving in stationary caps with ball-races in combination 85 with a resilient scraper adapted to remove from its inner surface the particles of the condensing water substantially as described.

3. In a machine for steaming cloth a perforated cylinder in combination with a stationary scoop longitudinally extending through the cylinder, provided with a bottom inclined from the middle toward both ends, and carrying a resilient scraper adapted to remove 90 from the inner surface of the cylinder the particles of the condensing water, substantially as described.

In testimony whereof I affix my signature.

GUSTAV BERNHARD GERLACH.

In presence of—

F. STEPHAN,
C. SCHNABEL.
